C. L. TARKET,
LINE OR CABLE UNION,
APPLICATION FILED NOV. 15, 1919.

1,409,430.

Patented Mar. 14, 1922.

Inventor:
Charles L. Tarket.
By: Albert C. Janner
Atty.

UNITED STATES PATENT OFFICE.

CHARLES L. TARKET, OF WATERBURY, CONNECTICUT.

LINE OR CABLE UNION.

1,409,430.

Specification of Letters Patent. Patented Mar. 14, 1922.

Application filed November 15, 1919. Serial No. 338,195.

To all whom it may concern:

Be it known that I, CHARLES L. TARKET, a citizen of the United States, and a resident of Waterbury, in the county of New Haven and State of Connecticut, have invented certain new and useful Improvements in Line or Cable Unions, which improvements are fully set forth in the following specification.

10 This invention relates to improvements in devices of that class available for adjustably securing together the opposite end-portions, or separate segments, of a line, cable or the like, such devices being well-designed line or cable unions.

15 The object of this invention is to provide a line or cable union which shall be simple and comparatively inexpensive as regards its construction; durable, efficient and reliable in practical service; measurably automatic in action; and which shall possess certain well-defined advantages over prior analogous constructions.

20 The invention consists in certain combinations, details and parts whereby, together with the novel disposition and relative arrangement of said parts, the attainment of the foregoing object is rendered practicable, all of which will be hereinafter more specifically referred to and set forth in the claims 25 hereto appended.

The invention is clearly illustrated in the accompanying drawing, wherein:

25 Fig. 1 is a face or diagrammatic view of a sheet-metal blank usable in the formation of the channeled body of a line or cable union embodying my said improvements.

Fig. 2 is a top plan view of the union.

30 Fig. 3 is a central, vertical, longitudinal section of same, as along the dotted line 3—3 of Fig. 2.

Fig. 4 is a vertical, transverse section thereof, as along the dotted line 4—4 of Fig. 2.

45 Referring to the accompanying drawing, wherein similar reference-numerals denote like parts throughout the several views, I, in carrying out my present invention, make use of a body, duly elongated and essentially 50 comprising opposite side-members 5, 5', up-standing in parallelism and connected along

opposite, longitudinal edges thereof by an intermediate tie-member 5", the entire body being preferably formed integral from a suitable sheet-metal blank, substantially as 55 illustrated in Fig. 1, said blank being primarily duly pierced and drawn up, as through the medium of suitable piercing and blanking dies, and the drawing-up process being such as to ensure for the completed body the general channeled form 60 herein contemplated, the opposite side-members 5, 5' being held duly spaced apart through the medium of the tie-member 5", as will be readily understood. 65

Primarily the blank aforesaid is so pierced in the process of its formation as to provide therefor opposite, elongated openings 6, 6', arranged convergent forwardly to the longitudinal center-line of the blank, 70 and sequentially divergent rearwardly thereto, whereby the openings 6, 6' become, upon the blank aforesaid being drawn up as stated, positioned at the opposite sides of the body of the device, in the opposite side-members thereof, and inclined; each from a point relatively near the free margin of the side-member wherein it is formed, to and terminates at a point suitably adjacent the tie-member 5". 75

6" is a pintle intersecting the opposite side-members of the device by way of the openings 6, 6', and freely workable to and fro within said openings, said pintle having a relatively small sheave or roller 7 85 mounted firmly thereon, as by a drive-fit, and the same and the sheave or roller carried thereby constituting, in co-operation with the openings 6, 6', a line-clamp, normally automatic and active in the general 90 operation of the device. 80

It may be here pointed out that when the line-clamp is held, by finger-pressure or otherwise, retracted, say, to the opposite termini of the openings 6, 6' most elevated 95 from the tie-member 5", an end-portion of a line, rope, cable, or the like, may be passed endwise within the channel of the body aforesaid, from the advance end thereof, and hence caused to lie between said line-clamp and the inner face of the tie-member 5". Said line-clamp being now released, 100

the same will, the device being duly held by the user to this end, move automatically forwardly and downwardly into clamping or locking engagement with the line, or the like, still positioned between the same and the tie-member aforesaid, such movement forwardly and downwardly on the part of the line-clamp being determined by the openings 6, 6', wherein the pintle of the line-clamp operates, and the aforesaid clamping or locking effect being intensified proportionately to any tendency on the part of the line or the like so clamped or locked to retreat, either through contraction of the line, or the like, itself, due to weather or other conditions, or any retractive stress otherwise brought to bear thereon, from its occupancy of, or positioned within, the body aforesaid.

20 The line or the like may now be released from the above-mentioned clamping or locking effect, by retracting along the openings 6, 6', by finger-pressure or otherwise, the line-clamp of the device, or by exerting on 25 the clamped or locked line, or the like, a suitable, direct pull, as will be clearly understood.

To facilitate the manipulation of the clamped line, or the like, for the release 30 thereof from the clamping effect aforesaid, I provide the body of the device with a leading-off guard 7', best fitted with an active face conforming approximately to the arc of a circle, and, in some instances, taking a general volute or clock-spring form, the same being constructed integral with the body of the device, by preference, as by oppositely slitting the blank aforesaid, along, say, the lines 8, 8', for the formation of an intermediate strip 8" connected with said body, particularly the tie-member 5" thereof, only at its inner end and being curved or turned suitably downwardly and forwardly, or coiled more or less upon itself as found 45 convenient or desirable in practice, the rear face of such guard constituting its active face, and downwardly along which passes the line or the like to be manipulated, to a position more or less returned relatively 50 thereto, all as clearly illustrated in Fig. 3.

Any appropriate medium may be availed of for facilitating the attachment of the device, as is needful in practice, to the end-portion of the line, or the like, opposite to 55 the end portion thereof to be clamped as herein explained, as in the case of a so-called "pulley" clothes-line, or to the end-portion of a separate section of another line, or the like, though to the attainment of this end I 60 provide the body aforesaid, and formed particularly in the side-members thereof, with transversely registering pin-receiving openings 9, 9', and positioned jointly within which and hence transversely of the body, is 65 an attaching-pin 9" around which, within

the channel of the body, may be secured said end-portion of the line, or the like, intended to be more or less permanently attached to or conjoined with the device, in service, all as clearly shown in Fig. 3.

70 The operation of my improved line or cable union will be apparent from the foregoing description thereof; and it will be noted that the device is not only well adapted for the purposes for which it is intended, particularly as a union for so-called "pulley" clothes-lines and whereby the same may be conveniently and dependably rendered duly taut, as found needful in practice, but that the same may be modified to a considerable extent, particularly as regards the specific character of the line-clamp made use of, the specific form and method of producing the body aforesaid, including the material used in the production of said body, and various minor details of the general construction, without materially departing from the spirit and principle of my invention as coming within the scope of the claims hereto appended.

90 I claim:

1. A line or cable union comprising a body consisting only of a base having suitable side-members rising therefrom at the opposite side-edges thereof, said side-members forming with said base an open channel for the reception of an end-portion of a line or the like to be clamped, and being fitted with complementary slot-like openings jointly extending upwardly and rearwardly away 100 from the base aforesaid or points adjacent thereto; and a line-clamp, the latter operating in the complementary openings aforesaid and being thereby rendered movable into and out of a line-clamping position 105 within said channel and relatively to said base, the device as a whole being fitted at its rear end-portion with a suitable line-attaching medium, and a portion of the material of said base being struck or drawn downwardly 110 for the formation, integrally therewith and at a point along the base well in advance of the line-attaching medium aforesaid, of a downwardly and forwardly curved leading-off guard.

115 2. A line or cable union comprising a body consisting only of a base having suitable side-members rising therefrom at the opposite side-edges thereof, said side-members forming with said base an open channel for 120 the reception of an end-portion of a line or the like to be clamped, and being fitted with complementary slot-like openings jointly extending upwardly and rearwardly away from the base aforesaid or points adjacent 125 thereto; and a line-clamp, the latter operating in the complementary openings aforesaid and being thereby rendered movable into and out of a line-clamping position 130 within said channel and relatively to said

base, the device as a whole being fitted with a line-attaching medium, consisting of a pin traversing transversely the channel aforesaid and piercing said opposite side-members at the rear end-portions thereof, and a portion of the material of said base being struck or drawn downwardly for the forma-

tion, integrally therewith and at a point along the base, well in advance of the line-attaching medium aforesaid, of a downwardly and forwardly curved leading-off 10 guard, the side-members according projecting rearwardly well beyond said guard.

CHARLES L. TARKET.
